UNITED STATES PATENT OFFICE

93,106

DESIGN FOR A FLATIRON OR LIKE ARTICLE

Russell I. Huffman, Strasburg, Ohio, assignor to
Thomas A. Edison, Incorporated, West Orange,
N. J., a corporation of New Jersey

Application April 24, 1934, Serial No. 51,496

Term of patent 7 years

To all whom it may concern:

Be it known that I, RUSSELL I. HUFFMAN, a citizen of the United States, residing in Strasburg, county of Tuscarawas, and State of Ohio, have invented a new, original, and ornamental Design for Flat Iron or Like Article, of which the following is a specification, reference being had to the accompanying drawing, forming a part of this specification:

In the drawing:

Fig. 1 is a perspective view of a flat iron showing my new design;

Fig. 2 is a plan view; and

Fig. 3 is a side elevation of the same.

The dominant feature of my design consists of the general configuration of the body and handle of the flat iron substantially as shown in the drawing.

I claim:

The ornamental design for a flat iron or like article, substantially as shown and described.

Signed at Strasburg, in the county of Tuscarawas and State of Ohio, on this 18th day of April, 1934.

RUSSELL I. HUFFMAN.
